UNITED STATES PATENT OFFICE

HYMAN TAUBER, OF GREENSBURG, PENNSYLVANIA, ASSIGNOR TO PORCELIER MANUFACTURING COMPANY, OF GREENSBURG, PENNSYLVANIA, A CORPORATION OF PENNSYLVANIA

DESIGN FOR A LIGHTING-FIXTURE BRACKET

Application filed July 12, 1930. Serial No. 36,333. Term of patent 7 years.

To all whom it may concern:

Be it known that I, HYMAN TAUBER, a citizen of the United States, residing at Greensburg, in the county of Westmoreland and State of Pennsylvania, have invented a certain new, original, and ornamental Design for a Lighting-Fixture Bracket, of which the following is a specification, reference being had to the accompanying drawings, forming a part hereof.

I claim:
The ornamental design for a lighting fixture bracket as shown.

In testimony whereof, I have hereunto subscribed my name this 3rd day of July, 1930.

HYMAN TAUBER.
